Primary Examiner—Philip S. Hyder*Assistant Examiner*—Adir Aronovich*Attorney, Agent, or Firm*—Roger A. Fields**[57]****CLAIM**

The ornamental design for a camera with an extendable lens and foldable flash, as shown.

DESCRIPTION

FIG. 1 is a front, top, right-side, perspective view of a camera with an extendable lens in a retracted position and with a foldable flash in a folded position, showing my new design;

FIG. 2 is a rear, bottom, left-side, perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right-side elevation view thereof;

FIG. 8 is a left-side elevation view thereof;

FIG. 9 is a front elevation view thereof, with the foldable flash in an unfolded position;

FIG. 10 is a rear elevation view thereof;

FIG. 11 is a top plan view thereof;

FIG. 12 is a bottom plan view thereof;

FIG. 13 is a right-side elevation view thereof;

FIG. 14 is a left-side elevation view thereof;

FIG. 15 is a front elevation view thereof, with the extendable lens in an extended position;

FIG. 16 is a top plan view thereof;

FIG. 17 is a bottom plan view thereof;

FIG. 18 is a right-side elevation view thereof; and,

FIG. 19 is a left-side elevation view thereof.
